DOOR LOCK

Edward A. Erhardt, Mission Beach, Calif., assignor to The Youngstown Steel Door Company, Cleveland, Ohio, a corporation of Ohio

Application January 28, 1942, Serial No. 428,581

6 Claims. (Cl. 292—281)

This invention relates to door locks and is primarily directed to locks for sliding doors of railway house cars.

It is an object of this invention to provide locks for sliding doors capable of automatically absorbing slack created by the movement of the doors.

A further object is to provide locks for sliding doors embodying locking pins and members wherein direct engagement between the pins and the members is avoided.

A further object is to provide locks for sliding doors embodying tapered locking pins wherein vertical movement of said doors relative to the car side or to adjacent doors will not produce upward movement of the pins.

Other objects of the invention will become clear as the description thereof proceeds.

In the drawing forming part of this specification:

Fig. 1 is an elevation showing a lock embodying the instant invention applied to a double door construction of railway house cars.

Fig. 2 is a horizontal section taken on line 2—2 of Fig. 1.

Fig. 3 is a vertical section taken on line 3—3 of Fig. 1.

Referring to the drawing wherein a preferred embodiment of the invention is illustrated, a lock is shown applied to the main and auxiliary doors of a double door construction for railway house cars. It will be apparent, however, to those skilled in the art that the invention is applicable as well to the single doors of railway house cars.

The main door 10 of the double door construction, utilized for purposes of illustration, embodies a metallic panel 11 formed with horizontal corrugations 12 merging at their ends into vertical corrugations, one of which is illustrated at 13 adjacent to the forward edge of the door. The door is reinforced by means of a backing plate 14 which spans the vertical corrugation and by means of a reinforcing member 15 secured to the forward margin of the door upon the outside of the panel as illustrated in Fig. 2 of the drawing. This construction of the main door is well known.

The auxiliary door 16 utilized in connection with the main door to constitute the double door construction is also well known and embodies a metallic panel 17 formed with horizontal corrugations 18 merging at their ends into vertical corrugations, one of which is shown at 19. A metallic door post 20 is secured to the forward margin of the auxiliary door and extends in-

wardly therefrom as shown in Fig. 2 of the drawing. A substantially Z-shaped stop member 21 is secured to the front margin of the auxiliary door between the metallic panel 16 and the door post 20 and cooperates with the latter to provide a pocket 22 for receiving the forward portion of the main door when the doors are closed. A knee brace 23 secured to the post and to the metallic panel reinforces the post.

The lock embodying the instant invention comprises a fastener 24 secured upon the outside of one of the horizontal corrugations 12 of the main door which at this point is reinforced by means of a member 25 disposed within said corrugation. The reinforcing member 25 extends into the vertical corrugation 13 as best illustrated in Fig. 2 of the drawing.

A locking member 26 is swingably supported by the fastener 24 as shown in Fig. 2 of the drawing. This member is formed with an inwardly extending locking detent 27 which carries a flange 28.

A lock bracket 29 is secured upon the outside of a horizontal corrugation of the auxiliary door 16 which is aligned with the horizontal corrugation 12 of the main door upon which the fastener is secured. The lock bracket 29 comprises vertically spaced housing members 30 and 31 which slidably receive a tapered locking pin 32. The housing member 30 is extended forwardly to provide a pocket 33 adapted to receive the upper end of a pivoted lever 34. The housing 31 is also extended forwardly to provide outer and inner spaced walls 35 and 36 between which the lever 34 is disposed and upon which said lever is pivotally supported by means of the pin 37. The lever 34 extends downwardly below the pin 37 so that the lever is pivoted intermediate its ends.

The rear face of the lever 34 intermediate the housing extensions is concave as indicated at 38. The cooperating face 39 of the locking detent 27 which is adapted to have locking engagement with the concave face of the lever 34 is convex, as more clearly shown in Fig. 1 of the drawing.

To lock the main and auxiliary doors together the detent 27 is engaged with the concave portion of the rear face of the lever 34. The tapered pin is then inserted through the housings 30 and 31 in forwardly overlapping relationship with the flange 28 provided on the detent. A seal not shown is then threaded through aligned slots 40 and 41 formed respectively in the pin 32 and in flange 42 of the lock bracket. The doors are then fully locked and it is to be observed that

the lower end of the lever 34 abuts the adjacent side of the tapered pin 32.

In the event that the doors are not fully closed when locked the main door may move in closing direction relative to the auxiliary door but separating movement between the doors is prevented by the locking engagement between the 5 detent on the locking member and the lever. Upon relative movement of the main and auxiliary doors in closing direction the locking 10 detent is released from the lever 34 so that the pressure of the lower portion of the lever against the adjacent side of the pin 32 is relieved. The pin thereupon will drop by the action of gravity and effect counter-clockwise swinging movement 15 of the lever so that locking engagement between detent 27 and the lever is restored. In this manner movement of the main and auxiliary doors toward each other may be continued until the doors are in contact, as illustrated in Fig. 2 of 20 the drawing, whereupon all movement in opening and in closing directions is precluded. Lashing of the doors with consequent wear and destruction of the lock is obviated.

It has been found that upon impact to house 25 cars the main and auxiliary doors thereof are subjected to relative vertical movement which when the locking members were disposed in direct locking engagement with the pins caused an upward creeping movement of the pins and, 30 in some instances, shearing of the seals. By the instant invention this locking engagement has been shifted from the pin to the lever 34 and by the provision of the curved cooperating faces between the locking detent 27 and the lever 35 the effect of the relative vertical movement between the doors has been eliminated.

It will be apparent that numerous changes and modifications in the details of the invention will be clear to those skilled in the art. It is intended, therefore, that all such modifications and changes be comprehended within this invention, which is to be limited only by the scope of the claims appended hereto.

I claim:

1. A lock for sliding doors comprising a lock bracket, a vertically slidable tapered pin carried by said bracket, a member pivotally mounted intermediate its ends on said bracket, and a swingably mounted locking element, said locking element being adapted to extend in front of said member at one side of the pivot for said member, an inwardly extending detent on said locking element engageable in locking relationship with said member, a flange extending from said detent and adapted to lie behind said pin, said member being engageable with a side of said pin at the other side of the pivot for said member.

2. A lock for sliding doors comprising a lock bracket, vertically spaced housings on said bracket, a tapered pin slidable in said housings, a member pivotally mounted intermediate its

ends in the lower of said housings, and a swingably mounted locking element, said locking element being adapted to extend in front of said member at one side of the pivot for said member, an inwardly extending detent on said locking element engageable in locking relationship with said member, a flange extending from said detent and adapted to lie behind said pin, said member being engageable with a side of said pin at the other side of the pivot for said member.

3. A lock for sliding doors comprising a lock bracket, a vertically slidable tapered pin carried by said bracket, a member pivotally mounted intermediate its ends on said bracket, and a swingably mounted locking element adapted to extend across said member at one side of the pivot for said member, said locking element having a detent engageable in locking relationship with said member, said member being engageable with a side of said pin at the other side of the pivot for said member.

4. In a railway house car having a horizontally sliding door and a relatively stationary member associated therewith, a lock bracket secured to said relatively stationary member, a vertically slidable tapered pin carried by said bracket, a lever on said relatively stationary member, said lever being pivotally mounted intermediate its ends and a locking element swingably mounted on said door, said locking element being adapted to extend across said lever at one side of the lever pivot, a detent on said locking element engageable in locking relationship with said lever, said lever being engageable with a side of said pin at the other side of the lever pivot.

5. A lock for sliding doors comprising a lock bracket, a vertically slidable tapered pin carried by said bracket, a member pivotally mounted intermediate its ends on said bracket, and a swingably mounted locking element adapted to extend across said member at one side of the pivot for said member, the side of said member adjacent to said pin having a curved portion, 45 said locking element having a detent provided with a curved face engageable in locking relationship with the curved portion of said member, said member being engageable with a side of said pin at the other side of the pivot for said member.

6. A lock for sliding doors comprising a lock bracket, a vertically slidable tapered pin carried by said bracket, a lever pivotally mounted intermediate its ends on said bracket, and a swingably mounted locking element adapted to extend across said lever at one side of the lever pivot, the side of said lever adjacent to said pin having a concave portion, said locking element having a detent provided with a convex face engageable in locking relationship with the concave portion of said lever, said lever being engageable with a side of said pin at the other side of the lever pivot.

EDWARD A. ERHARDT.
